(57) **CLAIM**

The ornamental design for a toy element, as shown and described.

DESCRIPTION

FIG. 1 is a top perspective view of a toy element of the present invention;

FIG. 2 is a front elevational view of the invention shown in FIG. 1;

FIG. 3 is a rear elevational view of the invention shown in FIG. 1;

FIG. 4 is a left side elevational view of the invention shown in FIG. 1;

FIG. 5 is a right side elevational view of the invention shown in FIG. 1;

FIG. 6 is a top plan view of the invention shown in FIG. 1; and,

FIG. 7 is a bottom plan view of the invention shown in FIG. 1. The shade lines shown in the drawing represent the three-dimensional contours of the toy element, and are not intended to indicate surface decoration.

1 Claim, 4 Drawing Sheets
